PERPETUAL CALENDAR

Louis E. Gould, Peace Dale, R. I.

Application March 25, 1933, Serial No. 662,777

7 Claims. (Cl. 40—107)

The present invention relates to new and useful improvements in perpetual calendars and has for some of its objects to provide, in a manner as hereinafter set forth, a calendar of this character

which will be simple in construction, strong, durable, reliable in use, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

15 Figure 1 is a view in front elevation of a perpetual calendar constructed in accordance with the present invention.

Figure 2 is a detail view in front elevation of the outer or rear disk, which will be hereinafter referred to as the day disk.

Figure 3 is a detail view in front elevation of the inner disk, which will be hereinafter referred to as the moon disk.

Figure 4 is a detail view in vertical section, taken substantially on the line 4—4 of Figure 1.

Figure 5 is a view in horizontal section, taken substantially on the line 5—5 of Figure 4.

Figure 6 is a horizontal sectional view, taken substantially on the line 6—6 of Figure 1.

30 Figure 7 is a view in front elevation, showing the means for frictionally mounting the month hand for adjustment on the calendar.

Figure 8 is a detail view in perspective of the main shaft, showing a portion of the day disk in which said main shaft is fixed.

Figure 9 is a detail view in perspective of the thrust sleeve.

Referring now to the drawings in detail, it will be seen that the embodiment of the invention which has been illustrated comprises a face plate 1 of suitable material, preferably heavy cardboard, having suspension means thereon, as at 2, for mounting the calendar on a wall or other support. Arranged in a circular series on the front of the face plate 1 are date numerals 3 from 1 to 31, inclusive. The front of the face plate 1 is also provided with the names of the months of the year equi-distantly spaced in a circular series within the dates 3, as at 4.

50 Fixed in the face plate 1 centrally with respect to the days and months 3 and 4 is a tubular bearing 5 having a head 6 integral with one end thereof and engaged against the rear of said face plate 1. Prongs 7 on the periphery of the head 6 penetrate the face plate 1 and are clinched, as

best seen in Figure 6 of the drawings, in a manner to secure the bearing 5 in position. A washer 8 is mounted on the bearing 5 in front of the face plate 1.

Mounted for rotary adjustment on the forward portion of the bearing 5 is a month hand 9, said month hand being immediately adjacent the washer 8. The month hand 9 is frictionally secured in adjusted position on the bearing 5 through the medium of resilient clamping jaws 10 which are secured, at one end, on an intermediate portion of said month hand 9, and which have their other end portions engaged in an annular groove 11 which is provided therefor in the forward end portion of the bearing 5. It will thus be seen that the clamping jaws 10 provide means for retaining the month hand 9 in position on the bearing 5 in addition to frictionally securing said month hand in adjusted position. The month hand 9 terminates adjacent the months 4 75 on the face plate 1, as seen in Figure 1 of the drawings.

The reference numeral 12 designates the day disk which is rotatably mounted rearwardly of the face plate 1 through the medium of a threaded shaft 13 which is journaled in the bearing 5, said shaft 13 projecting forwardly from the bearing 5. The shaft 13 is fixed centrally in the day disk 12 through the medium of an integral head 14 on the rear end of said shaft, prongs 15 on the periphery of the head 14 penetrating the day disk 12 and being clinched. Printed on the front of the marginal portion of the day disk 12, as at 16, are the days of the weeks which are repeated to provide 31 days arranged substantially consecutively reading from right to left, said days 16 forming a circular series spaced inwardly from the periphery of the disk 12. Also, on the disk 12, between the days 16 and the periphery of said disk, are the days of a single week, as at 17, said days 17 being printed in a distinguishing color, preferably red. The single week days 17 are also arranged consecutively reading from right to left. The days 17 are positioned radially with respect to the adjacent days 16.

Mounted on the shaft 13 between the day disk 12 and the face plate 1 is moon disk 18 of less diameter than said disk 12. The front of the disk 18 is provided with an elongated, arcuate, concentric representation 19 of a moon which is preferably colored red. A washer 20 is mounted on the shaft 13 between the moon disk 18 and the head 6 of the bearing 5. If desired, a similar washer may be provided on the shaft 13 between the disks 12 and 18.

100

105

110

The reference numeral 21 designates a thrust sleeve which encircles the shaft 13 in the bearing 5, said thrust sleeve being of greater length than the bearing 5 and having one end engaged with the washer 20. A date hand 22 is mounted for rotary adjustment on the shaft 13 and engaged with the forward end of the sleeve 21. A retaining nut 23 is threaded on the forward end portion of the shaft 13 and engaged with the date hand 22. It will thus be seen that by tightening the nut 23 the date hand 22 and the disks 12 and 18 will be frictionally secured together and it will further be seen that by loosening said nut 23 the date hand 22 and the disks 12 and 18 may be manually adjusted relative to each other and to the face plate 1. In its lower portion, the face plate 1 is provided with a cut out 24 to facilitate adjustment of the disks 12 and 18 when setting the calendar for each day. Above the bearing 5, the face plate 1 is further provided with an opening 25 through which the moon 19 on the disk 18 is observed.

Above the dates 3, the face plate 1 is still further provided with a substantially rectangular opening 26 with which upwardly extending slots 27 communicate. Mounted for vertical adjustment in the opening 26 is a shutter 28 having a window 29 therein through which the days 16 or 17 are observed. The window 29 is formed by striking the material of the shutter 28 forwardly in a manner to provide an operating lip or handle 30. The vertical sides of the shutter 28 are formed to provide channels 31 for the reception of the adjacent portions of the face plate 1 for slidably mounting said shutter in the opening 26. As will be apparent, when the shutter 28 is in its lower position, the days 16 may be observed through the window 29 and when said shutter is elevated to its raised position, the days 17 may be observed through the window 29. The slots 27 accommodate the shutter 28. Adjacent the opening 26 appears the year, as at 32, on the front of the face plate 1. By changing the year 32, the calendar may be used year after year until worn out. Advertising indicia or ornamental matter may be provided on the front of the face plate 1.

Briefly, the operation of the calendar is as follows:

Because of the fact that the months begin on different days, it is necessary to "set" the calendar on the first of each month. Also, because of the fact that each month begins on a different day, it is essential to start the calendar at the beginning of each month on one of the upper or red lettered days 17 and the shutter 28 is, therefore, moved to its raised position. The day disk 12 is then rotated manually until the desired day 17 appears in the window 29 of the shutter 28. Then, the disks 12 and 18 are secured in any suitable way against rotation relative to the face plate 1 while the nut 23 is loosened to permit adjustment of the date hand 22 to the numeral 1 of the dates 3. The nut 23 is again tightened to frictionally secure the date hand 22 and the disks 12 and 18 together. Of course, the month hand 9 is adjusted to indicate the correct month 4 on the face plate 1 by simply manually rotating said month hand on the bearing 5.

In order to keep the disk 12 of proper size, the annular row of week days 16 is limited to thirty-one and the extra week is placed at the top of the disk, as shown in Figure 2. It is necessary to have more than thirty-one week days on the disk in order to properly set the calendar at the beginning of a month. For instance, the month of January of the year 1933 be-

gins on a Sunday and ends on a Tuesday. Thus the first of February occurs on Wednesday and as February of 1933 only has twenty-eight days, the annular row of week days 16 can be used for these two months. However, if it should happen that the first of any month began on any other day except Sunday, there would not be enough days in the row 16 to appear correctly in proper sequence, for when the month begins on any other day except Sunday, when the last Tuesday is reached and Wednesday is due, the disk would begin to rotate again and Sunday would appear. Thus it is necessary to add six extra days to the week. It will be noted that the Sunday in the extra week 17 is located over a Sunday of the row 16 and by starting the first of a month, that does not come on Sunday, with a day of the extra week 17, it is simply necessary to move the shutter when Sunday of the row 17 appears so that Monday of the row 16 will be visible when the calendar is adjusted for the next day. This arrangement provides enough days on the disk to cover any month regardless of what day the first of the month comes on and by the use of the shutter, the black days are covered and the red days are exposed to start any month on the correct day and date.

To set the moon disk 18, the date of the month on which the first quarter of the moon occurs is ascertained, the date hand 22 is then moved to that date which, of course, imparts corresponding rotary movement to the day disk 12. Then, the day disk 12 is held stationary in any suitable manner while the nut 23 is loosened sufficiently to permit the moon disk 18 to be rotated until the representation 19 of the moon begins to appear in the opening 25 of the face plate 1 and the nut 23 is again tightened. Before again tightening the nut 23, it should be ascertained that the correct day 17 still appears in the window 29 of the shutter 28 and that the hand 22 still points to the correct date 3 on the face plate 1. Owing to the fact that the months are of different lengths, the representation 19 of the moon will not always be absolutely correct at all phases of all months but it will be substantially correct. The moon device is not meant to be an instrument of precision, but is added to the calendar as a novelty, and is substantially correct when properly "set".

The moon, as attached to the calendar, shows only from its first quarter to its last quarter and is not intended to show the new moon in the interim between the last quarter and the first quarter, because to do so would make the device too complicated.

From its first quarter, the moon gets a little larger each day until full moon, and then gradually gets a little smaller each day until the last quarter, and disappears. It can readily be seen that the shape of the area 19 must be concentric in shape to accomplish this result.

The reason it cannot be absolutely correct is, because on some months seventeen days elapse between the first and the last quarter, and during other months only fifteen days elapse for that same movement.

When drawing the area 19, an average was struck of the longest and shortest time between the first and last quarter of all months, and was incorporated into the calendar as a novelty, and not as an accurate instrument of precision. It may also be well to state that the calendar must be changed each day. As previously stated, the cut out 24 in the lower portion of the face

plate 1 facilitates manual adjustment of the disk 12 and 18.

It is believed that the many advantages of a perpetual calendar constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A perpetual calendar comprising, in combination, a face plate having the days of the months thereon and further having the months of the year thereon, coaxial disks rotatably mounted on the face plate, one of said disks being of greater diameter than the other, the larger disk having the days of the week in concentric series thereon, the smaller disk having a representation of the moon thereon, a month hand mounted for rotary, manual adjustment on the face plate for indicating the months, a date hand mounted for rotary adjustment relative to the face plate for indicating the dates on said face plate, means for securing the date hand and the disks together for rotary adjustment relative to each other and for rotatably mounting said date hand and the disks on the face plate, said face plate having an opening therein through which the representation of the moon may be observed and further having an opening therein for exposing the days on the large disk, and means for selectively exposing the concentric series of days on the large disk.

2. A perpetual calendar comprising, in combination, a face plate having the days of the months thereon and further having the months of the year thereon, coaxial disks rotatably mounted on the face plate, one of said disks being of greater diameter than the other, the larger disk having the days of the week in concentric series thereon, the smaller disk having a representation of the moon thereon, a month hand mounted for rotary, manual adjustment on the face plate for indicating the months, a date hand mounted for rotary adjustment relative to the face plate for indicating the dates on said face plate, means for securing the date hand and the disks together for rotary adjustment relative to each other and for rotatably mounting said date hand and the disks on the face plate, said face plate having an opening therein through which the representation of the moon may be observed and further having an opening therein for exposing the days on the large disk, and means for selectively exposing the concentric series of days on the large disk, the last named means including a shutter slidably mounted in the second named opening, said shutter having a window therein through which the days may be observed, a handle on the shutter for manually shifting said shutter, and channel members on the shutter slidably engaged with the face plate, the face plate still further having a cut out in a marginal portion thereof exposing peripheral portions of the disks for facilitating manual adjustment of said disks relative to said face plate.

3. A perpetual calendar comprising, in combination, a face plate having the days of the months thereon and further having the months of the year thereon, coaxial disks rotatably mounted on the face plate, one of said disks being of greater diameter than the other, the larger disk having the days of the week in concentric series thereon, the smaller disk having a representation of the moon thereon, a month hand mounted for rotary, manual adjustment on the face plate for indicating the months, a date hand mounted for rotary adjustment relative to the face plate for indicating the dates on said

face plate, means for securing the date hand and the disks together for rotary adjustment relative to each other and for rotatably mounting said date hand and the disks on the face plate, said face plate having an opening therein through which the representation of the moon may be observed and further having an opening therein for exposing the days on the large disk, and means for selectively exposing the concentric series of days on the large disk, the last named means including a shutter slidably mounted in the second named opening, said shutter having a window therein through which the days may be observed, a handle on the shutter for manually shifting said shutter, and channel members on the shutter slidably engaged with the face plate.

4. A perpetual calendar comprising, in combination, a face plate having the days of the months thereon and further having the months of the year thereon, coaxial disks rotatably mounted on the face plate, one of said disks being of greater diameter than the other, the larger disk having the days of the week in concentric series thereon, the smaller disk having a representation of the moon thereon, a month hand mounted for rotary, manual adjustment on the face plate for indicating the months, a date hand mounted for rotary adjustment relative to the face plate for indicating the dates on said face plate, means for securing the date hand and the disks together for rotary adjustment relative to each other and for rotatably mounting said date hand and the disks on the face plate, said face plate having an opening therein through which the representation of the moon may be observed and further having an opening therein for exposing the days on the large disk, and means for selectively exposing the concentric series of days on the large disk, the last named means including a shutter slidably mounted in the second named opening, said shutter having a window therein through which the days may be observed, a handle on the shutter for manually shifting said shutter, and channel members on the shutter slidably engaged with the face plate, the face plate still further having a cut out in a marginal portion thereof exposing peripheral portions of the disks for facilitating manual adjustment of said disks relative to said face plate.

5. A perpetual calendar comprising, in combination, a face plate having the days of the month thereon and the months of the year, a coaxial disk rotatably mounted on the face plate in rear thereof and having days of the week arranged in a concentric row thereon, a month hand mounted for rotary manual adjustment on the face plate for indicating the month, a date hand mounted for rotary adjustment relative to the face plate for indicating the dates on said face plate, means for securing the date hand and the disk together for rotary adjustment relative to each other and for rotatably mounting said date hand and the disk on the face plate, said face plate having an opening therein for exposing the days on the disk.

6. A perpetual calendar comprising, in combination, a face plate having the days of the month thereon and the months of the year, a coaxial disk rotatably mounted on the face plate in rear thereof and having days of the week arranged in a concentric row thereon, a month hand mounted for rotary manual adjustment on the face plate for indicating the month, a date

hand mounted for rotary adjustment relative to the face plate for indicating the dates on said face plate, means for securing the date hand and the disk together for rotary adjustment relative to each other and for rotatably mounting said date hand and the disk on the face plate, said face plate having an opening therein for exposing the days on the disk, said disk having an arcuate row of week days thereon for a single week, and means for selectively exposing the days of said single week or the days of the concentrically arranged row.

7. A perpetual calender comprising, in combination, a face plate having the days of the month thereon and the months of the year, a coaxial disk rotatably mounted on the face plate in rear thereof and having days of the week arranged in a concentric row thereon, a month

hand mounted for rotary manual adjustment on the face plate for indicating the month, a date hand mounted for rotary adjustment relative to the face plate for indicating the dates on said face plate, means for securing the date hand and the disk together for rotary adjustment relative to each other and for rotatably mounting said date hand and the disk on the face plate, said face plate having an opening therein for exposing the days on the disk, said disk having an arcuate row of week days thereon for a single week, means for selectively exposing the days of said single week or the days of the concentrically arranged row, the last named means including a shutter slidably mounted in the opening and having a window therein through which the days may be observed.
